UNITED STATES PATENT OFFICE.

JAMES M. TRIPLETT, OF WENATCHEE, WASHINGTON.

LOOP-SETTER.

1,097,483.

Specification of Letters Patent. Patented May 19, 1914.

Application filed November 26, 1912. Serial No. 733,628.

To all whom it may concern:

Be it known that I, JAMES M. TRIPLETT, a citizen of the United States, and a resident of Wenatchee, in the county of Chelan, 5 and State of Washington, have invented a new and Improved Loop-Setter, of which the following is a full, clear, and exact description.

This invention relates to moving picture 10 apparatus and has particular reference to a means for setting the loop of the film without interfering with the operation of the machine in the performance of its usual display functions.

15 Among the objects, therefore, of the invention, is to provide a mechanism of a simple nature under the immediate control of the operator of the machine whereby the loop may be set or shifted as may be required without stopping the machine or interfering with its intended purpose.

20 A further object of the invention is to devise an attachment adapted for use in connection with any standard moving picture machine, any changes necessary to 25 adapt the device for the various machines being of a simple and easily understood character.

The foregoing and other objects of the 30 invention will hereinafter be more fully described and claimed and illustrated in the drawings accompanying this specification in which like characters of reference indicate corresponding parts in all the views, and in 35 which—

Figure 1 is a rear elevation of a well known form of moving picture machine to which this improvement is applied; Fig. 2 is a vertical section taken at right angles to 40 Fig. 1 and showing the upper parts diagrammatically; Fig. 3 is a detail view showing the principal parts of my improvement in the position which they will occupy when setting the loop; Fig. 4 is a similar view 45 showing the parts in normal position; and Figs. 5 and 6 are detail perspective views of several parts described below.

Referring particularly to the drawings, I show, by way of illustration, a standard 50 form of moving picture apparatus 10 including a film 11. As usual, the film is operated downwardly from the upper magazine (not shown) between rollers 12, between an upper sprocket 13 and a tension 55 roller 14 where it forms a loop 15, thence passing over an upper film gate roller 16,

thence downwardly between an intermittent sprocket 17 and a lower film gate roller 18 forming a lower loop 19 and passing thence over a lower sprocket 20 and under a tension roller 21 to the lower magazine 22, where it is rolled upon a reel 23.

60 The foregoing description of the film and guiding means is to be understood as illustrative rather than in a limiting sense, the object of such description being to make it clear how the invention may be applied.

In practice there are times when the lower loop 19, for example, becomes taken up and the film is in danger of being broken 65 due to the direct pull thereon by the lower sprocket 20. In order to obviate this difficulty it is usual to stop the machine until the operator may make the proper adjustment of the film.

70 In carrying out this improvement in a preferred embodiment, I mount the lower sprocket 20 upon a transverse shaft 24 which is journaled in a bracket 25 carried by the main frame of the machine. Said 75 sprocket 20 is so mounted upon the shaft as to provide a certain amount of longitudinal relative movement between them as, for instance, by means of a slot 26 in one of the parts and a stud 27 projecting into said slot 80 from the other of said parts. The stud, however, will insure the simultaneous rotation of the sprocket and shaft. The sprocket 20 is intended to operate substantially snugly against one end of the bearing 85 25', and a pinion 28 is journaled loosely upon the shaft adjacent the other end of said bearing 25'. Said pinion 28 coöperates with any suitable gear 29 of the usual transmission mechanism of the machine and is 90 maintained in such meshing position by means of a flange 28'. To the opposite side of the pinion 28 is secured a clutch member 30 which is adapted to coöperate with a clutch member 31 secured to a pulley 32 100 from which the reel 23 is operated by means of a belt 33 under normal conditions. The pulley 32 is rigidly secured to the shaft 24 in any suitable manner and hence when the clutch members are interlocked, as shown in 105 Fig. 4, the shaft and sprocket 20 will be caused to rotate by reason of the rotation of the pinion 28 from the transmission mechanism including the gear 29.

Should it be desired, or necessary, to make 110 or lengthen the loop 19 of the film, it may readily be done by stopping the rotation of

the sprocket 20, the other parts of the film operating devices continuing in their regular movements. The result, therefore, will be that the loop 19 will be formed and when 5 of the proper size the sprocket 20 may again be started with corresponding rotation of the reel 23. The means I employ for stopping the operation of the sprocket 20 and reel includes the means shown in the form 10 of a lever 34 by which the shaft 24 is slipped laterally through the sprocket 20 and bearing 25' sufficiently far to disconnect the clutch members 30 and 31. The pinion 28 being loose on the shaft and maintained in 15 position with respect to the gear 29 will no longer transmit rotation to the shaft, but will continue rotating idly around the shaft 24. The means I prefer to employ for connecting the lever 34 to the shaft includes a 20 head 35 having loose pivotal connection at 36 with one end of the lever. The end of the shaft is extended into a socket 35 of the head and is provided with an annular groove 37 into which one or more screws 38 project 25 to prevent separation of the head and shaft but permitting free rotation of the shaft within the head. The lever 34 is pivoted upon the upper end of a bracket 39 and secured in any suitable rigid position with 30 respect to the machine.

At 40 is shown a spring surrounding the shaft 24 and acting at one end against the sprocket 20 and at the other end against a collar 41 adjustably connected to the shaft, 35 the tendency of such spring being to hold the clutch members 30 and 31 in normal engagement, as shown in Fig. 4. When, however, it is desired to set the loop, the operator will throw the lever 34 so as to cause 40 the shaft and collar 41 to operate against the tension of the spring 40 and throw the pulley 32 with its clutch member 31 away from the clutch member 30. When the proper loop is made, the operator, therefore, 45 fore, has but to release the lever 34, permitting the spring to throw the parts into their normal position.

The several parts of this attachment may be made of any suitable materials, and the

relative sizes, proportions and locations 50 thereof may be varied to a considerable extent, depending upon the type or character of the machine to which the attachment is to be applied, without departing from the spirit of the invention hereinafter claimed. 55

Having thus described my invention, I claim as new and desire to secure by Letters Patent:—

1. The herein described attachment for a moving picture machine comprising, in combination, a shaft, means to support the shaft for rotation, a sprocket secured to the shaft for rotation therewith, said supporting means holding the sprocket from longitudinal movement, means to rotate the shaft and 60 sprocket, said rotating means including a pinion loosely mounted on the shaft, the pinion having a flange to prevent it from shifting in a direction parallel to its axis, a pulley fixed to the shaft, and clutch members between the pinion and pulley normally connecting them together, and means to shift the shaft longitudinally with respect to the sprocket and pinion for the purpose of 65 stopping the operation of the sprocket while 70 the pinion may continue to rotate.

2. The herein described attachment for moving picture machines comprising a shaft, a support for the shaft, a film sprocket connected to the shaft for rotation therewith, 80 means to maintain the sprocket in fixed position with respect to the axis of the shaft, means to rotate the shaft including a clutch, one member of which is secured rigidly to 85 one end of the shaft, a non-rotary head loosely secured to the other end of the shaft, a lever under the control of the operator connected to the head for moving the shaft longitudinally of the sprocket to disconnect 90 the clutch, and means to automatically restore the parts to normal position.

In testimony whereof I have signed my name to this specification in the presence of two subscribing witnesses.

JAMES M. TRIPLETT.
